MACHINE FOR MAKING SPIRAL WINDINGS

Harris Watson Voorhees, Morrisville, Pa., assignor
to John A. Roebling's Sons Company, Trenton,
N. J., a corporation of New Jersey

Application November 30, 1935, Serial No. 52,292

6 Claims. (Cl. 153—65)

The present invention relates to mechanism for producing flexible metallic casings and more particularly to mechanism for producing flexible casings for Bowden wire mechanisms and composed of closely arranged spirals of relatively flat wire.

An object of the invention is to provide a machine for this purpose which will produce such spiral casings, the turns of which spirals are relatively close together but which have sufficient flexibility to perform the required functions of a Bowden wire casing.

Another object of the invention is to provide such a mechanism which will produce the required casing from two sources of flat wire supply, and in such a manner that of any two adjacent turns of the casing, each turn is formed from a different relatively flat wire from a separate wire supply.

A further object of the invention is to provide in the casing forming mechanism a push-off cam to force the wires axially along the casing being formed in relatively close relationship as the wires are formed into the spiral casing on a suitable mandrel associated with the push-off cam.

Other objects and advantages of the invention will appear from the following description taken in connection with the accompanying drawing which illustrates a preferred embodiment of the invention and in which:

Figure 1 is a sectional view through the casing forming mechanism, taken axially thereof and showing the wire supply reels and the spiral casing in process of formation;

Figure 2 is an enlarged side elevation of the push-off cam;

Figure 3 is a top plan view of the push-off cam of Figure 2, and

Figure 4 is a top plan view of the upper end of the guide tube.

Referring in detail to the drawing, a fixed anchor 11 is provided within which is made fast the lower end of the vertical stationary spindle 12.

Above the spindle anchor 11 is a sleeve block 13 within which is fixed a bearing sleeve 14, through which passes in an axial direction and interiorly spaced therefrom, the stationary spindle 12.

Rotatably mounted on the fixed bearing sleeve 14 is a reel carrier 15 having a lower sleeve portion 16 and an upper sleeve portion 17. To the lower sleeve portion 16 is keyed, as at 18, a driven gear 19, which is driven by a driving gear 20 in mesh with it, and itself power driven from any suitable source.

Fixed to the reel carrier and diametrically opposite each other are a pair of supply reel mounts 21 and 22 upon which are adjustably mounted, as at 23, the supply reels 24 and 25. The adjustable mountings are provided for the purpose of varying the takeoff angle made by the relatively flat

wires being withdrawn from the wire supply reels with the axis of the fixed spindle 12. It will be understood that when the desired adjustment has been effected the reels are locked in their adjusted positions and remain so locked as the gear driven reel carrier 15 rotates on sleeve 14 during the formation of the spiral casing. The tension on the wires is regulated by the thumb nuts shown on the spool ends.

Fixed, as at 26, within the upper sleeve portion 17 of the reel carrier is a guide tube 27, axially through which and in interiorly spaced relation thereto passes the fixed spindle 12.

The upper end of the guide tube 27 carries the push-off cam 28 which is fixed, as at 29, within the guide tube. The push-off cam is provided with an axial passage 30 through which passes the stationary spindle 12 which projects upwardly beyond the push-off cam and whose upper tapered end, lying within the formed spiral casing, is indicated by the dotted line 31. The extent of taper in the preferred embodiment is of the order of that shown in the drawing and indicated by the legend "Tapered" in Figure 1. The push-off cam 28 is provided with two diametrically opposite flat cam faces 32 and 33. Separating the two cam portions 32 and 33 are the opposite flat horizontal top portions 34 and 35 of the push-off cam.

The upper end of the guide tube 27 is provided with two opposite downwardly extending guide slots 36 and 37, the lower ends of which lie below the cam portions 32 and 33 of the push-off cam. These slots receive and guide upon the cam surfaces the relatively flat takeoff wires 38 and 39 being withdrawn from the supply reels 24 and 25, respectively, in edge on relation to the cam faces. The slots 36 and 37 are cut as shown in Fig. 4, to allow free access of the wires to the spindle when the spools approach exhaustion as well as when they are full.

A limit collar 27^a is affixed about the upper end of the guide tube 27; its lower end limits upward movement of the flat wires 38 and 39 near the fixed spindle and before they reach the spindle.

At the commencement of operation of the mechanism the wires from the takeoff reels may be laid by hand through their respective slots and initially wound spirally upon the upper end of the stationary spindle 12. Thereafter rotation of the gear driven reel carrier tends to wrap the lead-off wires 38 and 39 about the upper end of the spindle. With the parts in the position shown in Figure 1 the cam surface 32 of the push-off cam holds (in cooperation with the backing rolls 41 and 42 hereinafter referred to) the wire turns in close relation to each other.

Also, the abutment of the takeoff wire 38 on the cam surface 32 prevents downward movement of the takeoff wire 38 axially on the stationary

spindle 12, with the result that the cam causes a raising of the turns of the wire casing along and off the upper end of the spindle as the reel carrier 15 rotates. The turns of wire 39 are included in this push-off effect of cam 28, for it is evident that with the parts in the position of Figure 1, as there viewed, the lower edge of the first turn of wire 39 on the spindle abuts the upper edge of the first turn of wire 38 on the spindle, so that, 10 with the parts in the position shown, the cam, acting through wire 38, forces the turns of wire 39 along the spindle.

The slots 36 and 37 guide the wires onto the spindle, while allowing variations in the angle 15 formed by the takeoff wires and the spindle axis.

The functioning of either cam face, or of both cam faces, depends upon the adjustment of the reels to desired angular relation to the stationary spindle, upon which reel is used first to place 20 the first wire initially upon the spindle preliminary to starting the machine, and, during the operation of the machine, upon the varying angular relation of the takeoff wires to the spindle axis as the reels are unwound.

25 After the formed casing 40 leaves the spindle, it is passed between one or more pairs of circumferentially grooved rolls 41 and 42, which function to keep the twist in the casing backing on the spindle, after which the casing may pass 30 about an ordinary capstand to a take-up reel, not shown.

It will be understood that, while the invention is especially intended and is of especial value for use with flat wires, the broader features of the 35 invention are applicable also in forming spiral windings with wires of other form and such a machine is covered by the claims herein not limited to flat wires.

What is claimed is:

40 1. In a machine for making spirally wound flexible wire casings from a pair of relatively flat wires forming alternate turns of the casing, a rotatable reel carrier, a pair of wire supply reels oppositely arranged thereon, a stationary 45 spindle, means for pushing formed turns of alternate wires off said spindle comprising a push-off cam associated with said spindle, said cam having a pair of opposite push-off faces, and means for guiding a relatively flat wire from each supply reel to said spindle in edge on relation to a push-off cam face while allowing freedom of said wire to assume varying angular relation to said spindle comprising a guide member rotatable with said reel carrier and in fixed relation to said push-off cam, said guide member providing a pair of opposite radial wire guiding slots, one adjacent each push-off cam face, and means for rotating the reel carrier.

2. In a machine for making spirally wound 60 flexible wire casings from a pair of relatively flat wires forming alternate turns of the casing, a rotatable reel carrier, a pair of wire supply reels oppositely arranged thereon, a stationary spindle, means for varying the angular relation of said 65 reels to said spindle, means for pushing formed turns of alternate wires off said spindle comprising a push-off cam through which said spindle extends, said cam having a pair of opposite beveled flat push-off faces, and means for guiding a relatively flat wire from each supply reel to said spindle in edge on relation to a push-off cam face while allowing freedom of said wire

to assume varying angular relation to said spindle comprising a guide member rotatable with said reel carrier and in fixed relation to said push-off cam, said guide member providing a pair of opposite radial wire guiding slots, one adjacent each push-off cam face, means for backing the formed turns of the casing on the spindle, and means for rotating the reel carrier. 5

3. In a machine for making spirally wound 10 flexible wire casings from a pair of relatively flat wires forming alternate turns of the casing, a rotatable reel carrier, a pair of wire supply reels oppositely arranged thereon, a stationary spindle, means for varying the angular relation of said 15 reels to said spindle, means for pushing formed turns of alternate wires off said spindle comprising a push-off cam through which said spindle extends, said cam having a pair of opposite beveled flat push-off faces, and means for guiding a relatively flat wire from each supply reel 20 to said spindle in edge on relation to a push-off cam face while allowing freedom of said wire to assume varying angular relation to said spindle comprising a guide tube mounted in and rotatable with the reel carrier and having fixed therein, 25 intermediate its ends, said push-off cam, the end of said guide tube beyond the cam push-off faces having a pair of opposite radial wire guiding slots, one adjacent each push-off cam face, means for backing the formed turns of the casing on the 30 spindle, and means for rotating the reel carrier.

4. In a machine for making spirally wound 35 flexible wire casings from a pair of relatively flat wires forming alternate turns of the casing, a rotatable reel carrier, a pair of wire supply reels oppositely arranged thereon, a stationary spindle having a smooth tapered end, means for pushing formed turns of alternate wires off the tapered end of said spindle comprising a push-off cam 40 rotatable with respect to said spindle, a guide member rotatable with said cam and having wire guiding slots adjacent said cam between said cam and said wire supply reels, and means for rotating the reel carrier.

5. In a machine for making spirally wound 45 flexible wire casings from a pair of relatively flat wires forming alternate turns of the casing, a rotatable reel carrier, a pair of wire supply reels oppositely arranged thereon, a stationary spindle having a smooth tapered end, means for pushing formed turns of alternate wires off the tapered end of said spindle comprising a push-off cam rotatable with respect to said spindle, a guide member rotatable with said cam and having wire guiding slots adjacent said cam, and 50 adjustable slot-limiting collar fixed to said guide member, and means for rotating said reel carrier, guide member and push-off cam with respect to said spindle.

6. In a machine for making spirally wound 55 flexible wire casings from a pair of wires forming alternate turns of the casing, a rotatable reel carrier, a pair of wire supply reels oppositely arranged thereon, a stationary spindle having a smooth tapered end, means for pushing formed 60 turns of alternate wires off the tapered end of said spindle comprising a push-off cam rotatable with respect to said spindle, a guide member rotatable with said cam and means for rotating the reel carrier.
